REVERSE GEAR FOR OUTBOARD MOTOR
UNDERWATER UNITS

Elmer C. Kiekhaefer, Cedarburg, Wis.

Application December 23, 1950, Serial No. 202,479

8 Claims. (Cl. 115—17)

1

This invention relates to outboard motors and particularly to underwater reverse-gear propeller units and this application is a continuation in part of the copending application of the present inventor filed March 24, 1949, Serial No. 83,250 and entitled Engine Mounting and Control System.

The invention provides an improved mechanical actuation for control of the underwater unit.

A principal object of the invention is to provide greater ease of manual control of the lower underwater unit.

A more particular object is to provide an improved actuating lever for a lower underwater clutch unit with an axial movement in one direction against a spring operating in the opposite direction.

A further object is to reduce to a minimum the outer dimensions of the unit for maximum possible stream-lining while providing a serviceable, dependable shift mechanism within.

Another object is to provide a more positive clutch actuation and control.

These and other objects and advantages will be more fully set forth in the following description of a preferred embodiment of the invention as illustrated in the accompanying drawings.

In the drawings:

Figure 1 is a side elevation of an outboard motor with parts thereof broken away and sectioned.

Fig. 2 is an enlarged longitudinal vertical section of the lower end of the underwater unit of the motor shown in Figure 1;

Fig. 3 is a transverse vertical section of the underwater unit shown in Fig. 2;

Fig. 4 is a horizontal sectional view of the lower unit taken through the axis of the propeller shaft showing the clutch device in neutral position; and

Fig. 5 is a view similar to Fig. 4 showing the clutch in the position for reverse drive.

The outboard motor shown in the drawings includes the engine 1, shown in part, and the hollow cast drive shaft housing 2 which supports engine 1 thereon and carries the underwater unit 3 at the lower end thereof.

The drive shaft 4 connected directly to the lower end of the vertical engine crankshaft 5 extends downwardly through housing 2 into the housing 6 of unit 3.

Housing 6 comprises a single cast member and is secured to the lower end of housing 2 by the bolts 7 and 8.

2

The motor is supported by the screw-clamp bracket 9 adapted to be removably secured to the boat transom 10, shown in section in Fig. 1. The swivel bracket 11 is carried by bracket 9 for pivotal movement on the transverse pin 12 which provides for tilting of the motor and raising and lowering of the underwater unit 3.

The forward edge of housing 2 is recessed to receive bracket 11 and the vertical hollow pin or sleeve 13 carried by bracket 11 which projects upwardly and downwardly into bushings 14 set in the forward edge of housing 2. Pin 13 serves to support the motor for turning movement on a vertical axis as with the tiller 15 which turns the motor including lower unit 3 to control the direction of movement or steering of the boat.

The lower unit 3 includes the propeller 16 which is mounted rearwardly on the shaft 17.

The bearing 18 in the forward portion of housing 6 supports the forward end of shaft 17 therein and bearing 19 in housing 6 spaced rearwardly of bearing 18 supports the shaft intermediate its ends on the bushing 20 mounted on the shaft.

The forward bevel gear 21 is freely mounted on shaft 17 for rotation thereon or to rotate therewith. The rear bevel gear 22 is supported by the bearing 23 in housing 6 for rotation with or independently of shaft 17 on coincident axes.

The upper and lower bearings 24 and 25, respectively, journaly carry shaft 4 in housing 6 on a projected vertical axis intersecting the axis of shaft 4.

The gear 26 is secured by the bolt 27 to the splined lower end of shaft 4 to mesh with gears 21 and 22 and to drive the same in opposite directions.

Each of the gears 21 and 22 is formed with a series of clutch teeth 28 in adjacent faces and which are adapted to be engaged by the flat bar 29 carried in the slot 30 by shaft 17.

Bar 29 is axially movable within slot 30, and dimensioned so as to be selectively engageable with the teeth 28 of either of gears 21 or 22 or to be disposed between the gears and free thereof.

According to the invention, the movement of bar 29 is effected by rotating the vertical shaft 31 carried by housing 6 with the lower end thereof extending into the cavity 32 in housing 6 ahead of the forward end of shaft 17. The lower reduced end 33 of control shaft 31 is turned on a center which is eccentric from the center of the shaft body and forms the inner race of the roller bearings 34 in the retainer ring 35. A center hole drilled in the forward end of shaft 17 extends beyond slot 30 in the shaft to carry

the spring 36 in the forward end thereof and forwardly of slot 30.

The plug 37 and pin 38 are disposed in hole 35 and fit corresponding notches in the forward and rear edges of bar 29. The width of slot 30 provided in shaft 17 is narrower than the diameters of hole 35, or plug 37 and pin 38 so that the latter upon assembly secure bar 29 against displacement radially of shaft 17 as shown in Figs. 4 and 5. Spring 36 is compressed within hole 35 against plug 37 and normally urges bar 29 in a direction axially of shaft 17 into engagement with the teeth 28 of gear 21 to effect rotational engagement of gear 21 and shaft 17 to rotate propeller 16 for forward propulsion.

The forward end of pin 38 projects from the hole 35 in shaft 17 into cavity 32 and is disposed to be engaged by the outer retainer 35 of rollers 34 upon rotation of control shaft 31 as will be described. Rotation of control shaft 31 approximately 90° moves retainer 35 against pin 38 and moves bar 29 to a neutral position between gears 21 and 22 in which the bar is not in engagement with the teeth 28 of either gear. In such neutral position, engine 1 may be operating without driving the propeller 16.

Further rotation of control shaft 31 moves ring 35 retaining rollers 34 and through pin 38 pushes bar 29 against spring 36 and into engagement with teeth 28 of gear 22 to effect rotational engagement of gear 21 and shaft 17 to rotate propeller 16 in a reverse direction.

Rotation of control shaft 31 is effected by the control handle 39 which extends forwardly of the motor over tiller 15 and is mounted on the upper end of the control rod 40.

Control rod 40 is supported for rotation within pivot pin 13 and extends downwardly through the pin and the forward leading edge of housing 2.

The bore 41 in the forward leading edge of housing 6 is disposed to receive the lower end of rod 40 and supports shaft 31 therein rotationally. Shaft 31 is axially supported on the lower end 33 by the portion of housing 6 forming the lower face of cavity 32. The lower end 42 of rod 40 is squared to fit a corresponding square hole in the upper end of shaft 31 and rotationally secure rod 40 and shaft 31 for operation as described.

Rod 40 is disengageable from shaft 31 merely upon removal of the lower unit 3 from housing 2.

Shaft 31 is preferably of substantial diameter to provide the necessary movement of pin 38 which is determined by the radius or offset of the reduced end 33 of the shaft. The size of the shaft is easily accommodated vertically in the forward leading edge of housing 6 and within the desired dimensional limitations of the housing. Shaft 31 is rotationally disposed and supported substantially its entire length in bore 41 so that radial loads in turning against spring 36 will not bind the shaft.

The rollers 33 additionally assure ease of turning to effect shifting of bar 29 as described. Disassembly of lower unit 3 and housing 6 from housing 2 can accordingly be accomplished without attention to the control shift mechanism or disconnecting the same.

Various embodiments of the invention may be employed within the scope of the following claims.

I claim:

1. In an outboard motor supported at its upper end for pivotal movement on a hollow vertical pin and having a shift mechanism at its lower

end including an axially movable horizontal control pin, a vertical control shaft extending through said pivot pin and having an eccentric lower end adjacent to and engageable with one end of said control pin, and a manual control arm secured to the upper end of said control shaft above said pin for effecting rotation of said control shaft and movement of the eccentric lower end thereof and said control pin.

2. In an outboard motor, a drive shaft housing, a lower underwater streamlined gear housing carried by said drive shaft housing and having a chamber forwardly therein, a propeller shaft carried by said gear housing with one end of the shaft facing said chamber, driven gears rotating in opposite directions within said gear housing on the axis of said propeller shaft, drive means carried by said propeller shaft and axially movable with respect thereto and selectively into driving engagement with one of said gears to effect rotation of said shaft in either direction, said means including a pin carried by said shaft and projecting centrally from the end thereof into said chamber, and a vertical control shaft rotatably carried within the forward leading edge portion of said gear housing and having an eccentrically formed bearing member projecting into said chamber and engageable with said pin to move the latter upon rotation of said control shaft and to actuate said drive means.

3. An outboard motor including a drive shaft housing supported at its upper end for pivotal movement on a hollow vertical pin and having a shift mechanism at its lower end including an axially movable horizontal control pin, a lower underwater streamlined gear housing carried by said drive shaft housing and having a chamber forwardly therein, a propeller shaft carried by said gear housing with one end of said shaft facing said chamber, driven gears rotating in opposite directions within said gear housing on the axis of said propeller shaft, clutch means carried by said propeller shaft and axially movable with respect thereto and selectively into driving engagement with one of said gears to effect rotation of said shaft in either direction, said means including said pin carried by said shaft and projecting centrally from the end thereof into said chamber, a shaft rotatably carried by said gear housing having an eccentrically formed bearing member projecting into said chamber and engageable with said pin to move the latter upon rotation of said shaft and actuate said clutch means, a vertical control rod extending through said pivot pin and rotatably engageable with said shaft, and a manual control arm secured to the upper end of said control rod above said pin for effecting rotation of said first named shaft and movement of the eccentric lower bearing member and said pin.

4. In an outboard motor, a drive shaft housing, a lower underwater streamlined gear housing carried by said drive shaft housing and having a chamber forwardly therein, a propeller shaft carried by said gear housing with one end thereof facing said chamber, driven gears rotating in opposite directions within said gear housing on the axis of said propeller shaft, drive means carried by said propeller shaft and axially movable with respect thereto and selectively into driving engagement with one of said gears to effect rotation of said shaft in either direction, said means including a pin carried by said shaft and projecting centrally from the end thereof into said chamber

ber, a control shaft rotatably carried by said gear housing having a reduced eccentrically formed trunnion member projecting into said chamber and a roller bearing assembled on said bearing member and including an outer retaining race engageable with said pin to move the latter upon rotation of said control shaft and providing a surface engaging said pin endwise with substantially nominal angularity to actuate said drive means.

5. An outboard motor including a drive shaft housing supported at its upper end for pivotal movement on a hollow vertical pin and having a shift mechanism at its lower end including an axially movable horizontal control pin, a lower underwater streamlined gear housing carried by said drive shaft housing and having a chamber forwardly therein, a propeller shaft carried by said gear housing with one end of said shaft facing said chamber, driven gears rotating in opposite directions within said gear housing on the axis of said propeller shaft, clutch means carried by said propeller shaft and axially movable with respect thereto and selectively into driving engagement with one of said gears to effect rotation of said shaft in either direction, said means including said pin carried by said shaft and projecting centrally from the end thereof into said chamber, a shaft rotatably carried by said gear housing having an eccentrically disposed roller bearing unit slidably supported in said chamber and engageable with said pin to move the latter upon rotation of said shaft and actuate said clutch means, a vertical control rod extending through said pivot pin and rotatably engageable with said shaft, and a manual control arm secured to the upper end of said control rod above said pin for effecting rotation of said first-named shaft and movement of the eccentric lower bearing unit and said pin.

6. In an outboard motor including a hollow vertical pin supporting the motor for steering movement and having a shift mechanism at its lower end including an axially movable horizontal control pin, a vertical control rod extending through said pivot pin and having an eccentric roller bearing adjacent to and engageable with one end of said control pin, and a manual control arm secured to the upper end of said control shaft above said pin for effecting rotation of said bearing and movement of said control pin.

7. In an underwater lower unit for an outboard motor including a driving gear and oppositely disposed and spaced driven gears rotating in opposite directions on a single axis, a propeller shaft extending through said driven gears and journal supported on said axis, said driven gears having clutch teeth formed in adjacent faces thereof, a flat bar carried flatwise within a slot formed in said shaft between said driven gears, said bar projecting from said shaft radially thereof and movable in said slot be-

tween said driven gears into selective driving engagement with the clutch teeth of one thereof, said shaft having a central axial bore opening at one end thereof, a pin having one end thereof disposed in said bore and fitting in a notch centrally in the corresponding edge of said bar and movable longitudinally in said bore to move said bar in one direction in said slot, and spring means in said bore engaging said bar in a second notch in the corresponding other edge thereof and disposed to bias said bar in the opposite direction, said pin and spring means securing said bar against displacement in said slot radially of said shaft, and manually operable eccentric means engageable with the other end of said pin to effect movement of said pin and said bar in one direction and against said spring means to limit movement of said bar and said pin by said spring means in the other direction.

8. In an underwater lower unit for an outboard motor including a gear housing and oppositely disposed and spaced driven gears rotating in opposite directions on a single axis, a propeller shaft extending through said driven gears and journal supported within said housing on said axis, said driven gears having clutch teeth formed in adjacent faces thereof, a flat bar carried flatwise within a slot formed in said shaft between said driven gears, said bar projecting from said shaft and movable in said slot between said driven gears into selective driving engagement with the clutch teeth of one thereof, said shaft having a central axial bore opening at one end thereof, a pin having one end thereof disposed in said bore and fitting in a notch centrally in the corresponding edge of said bar and movable longitudinally to move said bar in one direction in said slot, and spring means in said bore engaging said bar in a second notch in the corresponding other edge thereof and disposed to bias said bar in the opposite direction, said pin and spring means securing said bar against displacement in said slot radially of said shaft, and a control shaft rotatably carried by said gear housing and having an eccentrically formed bearing portion engageable with the other end of said pin to effect movement of said pin and said bar in one direction and against said spring means to limit movement of said bar and said pin by said spring means in the other direction.
